Primary Examiner — Jae Liang
Assistant Examiner — Riya Salil Kamat(74) *Attorney, Agent, or Firm* — Hawaii Patent Services;
Nathaniel K. Fedde; Kenton N. Fedde(57) **CLAIM**

The ornamental design for a golf training strike net, as shown and described.

DESCRIPTION

FIG. 1 is a front, right, top perspective view of a golf training strike net, showing my new design;
 FIG. 2 is a rear, left, bottom perspective view thereof;
 FIG. 3 is a front elevational view thereof;
 FIG. 4 is a rear elevational view thereof;
 FIG. 5 is a left side view thereof;
 FIG. 6 is a right side view thereof;
 FIG. 7 is a top plan view thereof;
 FIG. 8 is a bottom plan view thereof;
 FIG. 9 is an enlarged view of detail 9 in FIG. 1;
 FIG. 10 is an enlarged view of detail 10 in FIG. 3; and,
 FIG. 11 is an enlarged view of detail 11 in FIG. 8.
 The dashed broken lines illustrate portions of the golf training strike net which form no part of the claimed design.
 The dash-dot-dash broken line depict the bounds of the enlarged views and form no part of the claimed design.
